Primary Examiner—Doris V. Coles

Attorney, Agent, or Firm—Michael R. Schacht; Hughes, Multer & Schacht, P.S.[57] **CLAIM**

The new design for a sword handle, as shown and described herein.

DESCRIPTION

FIG. 1 is a side elevational view of a sword handle, showing my new design;

FIG. 2 is an enlarged side elevational view, the opposite side being a mirror image thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view of a second embodiment, the opposite side being a mirror image thereof;

FIG. 8 is a top plan view thereof;

FIG. 9 is a bottom plan view thereof;

FIG. 10 is a front elevational view thereof; and,

FIG. 11 is a rear elevational view thereof.

The broken line showing of a blade in FIG. 1 and portions of a blade in FIGS. 2-4 and 7-9 is for illustrative purposes only and forms no part of the claimed design.
